REMOTE-CONTROL SYSTEM

Ellison S. Purington, Gloucester, Mass., assignor,
by mesne assignments, to Radio Corporation of
America, New York, N. Y., a corporation of
Delaware

Application April 5, 1945, Serial No. 586,781

10 Claims. (Cl. 250—2)

1

This invention relates to an improved method of remote control by radio, permitting the independent execution of two control operations. For example, as applied to the control of an airborne craft, it provides for left or right rudder, and also for up and down control of elevation, either independently or in combination.

One feature of the invention is that the system cannot be readily operated by the types of transmitters commonly available. Hence a considerable degree of security is provided.

Another feature is provision for the introduction of irrelevant signals so that unauthorized parties will be confused in making analysis of the system which is being employed.

In the operation of the invention a continuous carrier wave is radiated. This wave is then modulated by selected ones of four different signal frequencies applied in periodic succession, with substantially a quarter of the operating time devoted to each signaling channel. During selected cyclic periods of allotment of the signals to the multiplex channels alternating currents are built up in corresponding receiver channels, with phase separations by 90 electrical degrees, or multiples thereof. The control operations are determined by the phase relations of the currents by the use of phase comparator circuits.

Fig. 1 shows a form of transmitter;

Fig. 2 shows the first portion of a radio receiver 30 cooperating with the transmitter of Fig. 1;

Fig. 3 shows a tuned type phase comparator system for use with the receiver of Fig. 2;

Fig. 4 shows an aperiodic type phase comparator which can be used with the receiver of Fig. 2, 35 alternative to that of Fig. 3.

Fig. 5 illustrates a generalized method of operation in accordance with my invention.

In Fig. 1, a master carrier wave source 10 is operatively coupled through a capacitor 11 to a modulated power amplifier 20, which delivers amplified power output to antenna 30, modulated in accordance with the signal pattern impressed upon the control grid of modulator 40. The input circuit for tube 20 includes a choke 12 and a resistor 14 connecting the control grid to ground. Resistor 14 is shunted by a capacitor 13. The output circuit is fed with direct current anode potential from the source 17, connection being made from the anode through a choke 19

2

and the primary winding 21 of an output transformer. The inductance 21 is parallel-tuned by a capacitor 22. One end of the parallel-tuned circuit 21—22 is connected to ground through a capacitor 18 which is chosen as a low impedance to radio frequency currents and as a virtually infinite impedance to audio frequency currents. The transformer primary 21 is coupled to a secondary which feeds energy to the antenna 30. A cathode resistor 15 connects the cathode and suppressor grid to ground. This resistor is shunted by a capacitor 16. Screen grid potential is supplied from the source 17 through a resistor 23. The screen grid is connected to the cathode 13 through a capacitor 24.

Through the choke 19 anode potential is also fed to the anode of the amplifier tube 40. This tube is shown as a triode but other types of tubes may be used, of course, if desired. The cathode 20 is connected to ground through a cathode resistor 26 which is shunted by a capacitor 27. The input circuit includes a grid resistor 28 connecting the grid to ground. Connection is also made between the control grid and the slip ring of the 25 commutator 47 hereinafter to be described in more detail.

Four selectable frequency sources 41, 42, 43, 44 are provided, which may be operatively connected to the input of a modulator 40 under the control of relay devices 45 and 46, and in accordance with the operation of a commutator 47, driven by motor 49. The relays 45 and 46 in turn are controlled by key sets 51 and 52, with the former used for example for right or left rudder, and the latter used for example for up or down elevator.

As an illustrative example, the carrier frequency might be 100 megacycles. The frequencies of sources 41 to 44 have been designated f_1 , f_2 , f_3 , and f_4 . These frequencies, however, might be 52, 64, 56, and 68 kilocycles respectively, and the commutator device might be rotated at a frequency of 100 revolutions per second. The arrangement of the keys and relays shown provides 45 left-right control of the rudder and at the same time up-down control of the elevator. This is for illustration, and it will be understood other combinations are possible, namely right, left, up, down, all individually, or right-up, right-down, 50 left-up, left-down in combination. When a key

is in neutral, there is no operation corresponding to that key. These controls determine the order in which the various frequency sources are impressed upon the modulator 40 by the commutator device 47, and therefore the order at which peaks of energy occur in corresponding receiver circuits to be described later.

In more detail, the key 51 is provided with a moveable contact member 53, and contacts 55, 57. Contact 55 is connected through relay winding 59 and contact 57 is connected through relay winding 61 to ground, one side of battery 63 being grounded. The other side of this battery is connected to the moveable key contact. The windings 59 and 61 are on opposite legs of a balanced relay 45 having an armature 67 which is operatively connected by insulating member 69 to moveable blades 71, 73 of a double pole double throw reversing switch, with outer contacts 75, 77 joined together and to one terminal of source 41, and inner contact 79 connected to one terminal of source 43. The other terminals of sources 41 and 43 are grounded. Spring pressure is exerted opposingly against the insulator 69 by contacts 71 and 73, thus normally centering the relay armature 67 and breaking all contacts when neither of the windings 59 or 61 are actuated. The contacts 71 and 73 are connected respectively to segments 85 and 87. The commutator 47 has a slip ring 89 which is swept by a brush 93 mounted on a rotary brush arm 91 driven by a motor 49. The brush, therefore, connects each of the commutator segments in succession to the slip ring. The segments are insulated from each other, and occupy the four quadrants of the commutator periphery.

The key 52 for up and down operation, its associated relay 46 and commutator connections are similar to those for key 51 and need not be described in detail, other than to catalog the items. When the key 52 is moved to the up position contact 54 is engaged which energizes the winding 62 on relay 46. When the key is moved to the down position contact 56 is engaged which energizes winding 60 on this relay. The contact spring arrangement operated by relay 46 includes movable contacts 72 and 74, outer contacts 76 and 78, and the middle contact 80. The tone generators 42 and 44 are connected to the outer and inner contacts similarly to the connections described for generators 41 and 43 and their associated relay contacts. The movable contact 72 is connected to segment 84 on the commutator 47, while contact 74 is connected with commutator segment 86.

As previously stated, the slip ring 89 is connected to the input grid of modulator 40, which is connected to ground through resistor 28. As a result, the segments 87, 85, 86 and 84 are connected to the modulator 40 in rotary succession, so that its input is energized in succession from whatever voltages are impressed steadily upon these four segments.

With the choice of right-down control, as indicated, the sequence of this four frequency pattern will be f_1, f_3, f_2, f_4 , which sequence is repeated during each revolution of the brush arm 91 at a speed, say, of 100 revolutions per second.

It will be clear from the above description that remote control signals may be transmitted which are composed of a succession of different tone frequencies applied as modulations to the carrier wave generated by the source 10. The significance of each signal train will depend upon the selective connections of the tone generators to the commutator segments, or in other words,

upon the application of the tone frequencies as modulations in different sequences. If only one of the keys, say key 51, is actuated then a right indication will be represented by the immediate sequence of frequencies f_1 and f_3 in that order, while if this key is moved for left indication the frequencies will be f_3 and f_1 in that order. The key 52 being unactuated no modulation frequencies will be sent out while the brush 93 traverses segments 86 and 84. Other sequences of the tone frequency modulations or frequencies f_1, f_3, f_2 and f_4 may, of course, be transmitted, depending upon the remote control operations to be performed.

The modulating frequencies are recreated at the receiver by use of an arrangement such as shown in Fig. 2.

Signals from transmitter antenna 30 of Fig. 1 are received by antenna 100 of Fig. 2, tuned to carrier wave resonance by radio receiver 101, and impressed, either directly or after conversion to an intermediate frequency, upon the control grid of detector 102, preferably of the square law, plate detector type. The output is selectively transmitted through frequency discriminator 105 to energize amplifier 113 most completely from detected energy or frequencies corresponding to transmitter sources 41 and 43, for right-left control, and amplifier 114 most completely from detected energy or frequencies corresponding to transmitter sources 42 and 44 for up-down control. After amplification in 113, a further discriminator 117 actuates detectors 133 and 135 most strongly for the frequencies corresponding to sources 41 and 43. Similarly detectors 134, 136 are most strongly actuated from sources 42 and 44, the received signal energy being fed through the discriminator 118.

These detectors are provided with output circuits with designs such as to smooth out the detected outputs to produce voltages at terminals 163, 165, 164, 166 of the frequency corresponding to the rotation of commutator 47, but the relative phases of the currents will be determined by the signal sequence. For the transmitter case given, the voltage peak at terminal 163 will lead the voltage peak at terminal 165 by 90 electrical degrees, at 100 cycles per second, while the voltage peak at terminal 164 will lag behind the voltage peak at terminal 166 by 90 electrical degrees.

It will be understood by those skilled in the art that the choice of frequencies for actuation of the selective circuits is arbitrary, and need not conform to what is herein illustratively stated. Furthermore the circuits themselves may be modified in design, as for example, by use of more selective circuits, for the frequencies corresponding to transmitter sources 41 to 44 and for the output frequencies corresponding to the rotary speed of the motor 49.

In addition to the receiver equipment of Fig. 2, phase comparators are required for the outputs of Fig. 2. Although such devices have been shown elsewhere, they are not generally known and two arrangements are here shown. Fig. 3 shows a transformer type with inputs numbered to operate from the outputs of detectors 133 and 135, while Fig. 4 shows an aperiodic type with inputs numbered to operate from the outputs of detectors 134 and 136. Either type could be used in either place, and other phase operated devices might be substituted.

In Fig. 3, input terminal 163 is connected through resistor 163a to the grid of amplifier triode 169, which in turn is connected through condenser 163b to the grounded input terminal

167. Input terminal 165 is connected through condenser 165a to the grid of amplifier triode 170, which in turn is connected through resistor 165b to ground terminal 167. The impedances of elements 163a, 163b, 165a, 165b are all chosen to be substantially equal at the recurrence frequency, say 100 cycles, so that the voltage on the grid of triode 170 leads that on terminal 165, while that on the grid of triode 169 lags behind that on terminal 163 both by 45 electrical degrees.

The cathodes of triodes 169 and 170 are connected together and to the positive end of battery 171, the negative end of which is connected to ground terminal 167. The plate of tube 169 is connected through resonant circuit 173, 174 and the plate of 170 is connected through resonant circuit 175, 176 to the positive end of battery 172, the negative end of which is connected to the cathodes of tubes 169 and 170. The resonant circuits are tuned to the frequency of recurrence, such as 100 cycles in the illustrative case. If a convention is adopted that currents are positive in the direction shown, then the currents in coils 173 and 175 will be in phase provided the grids of tubes 169 and 170 are excited in phase, that is if the voltage at terminal 163 with respect to ground leads the voltage at terminal 165 with respect to ground by 90 electrical degrees. But if the voltage at terminal 163 lags behind that at terminal 165 by 90 degrees, then the grids of tubes 169 and 170 will differ in phase by 180 degrees, so that currents in resonant inductors 173, 175 will be oppositely phased. But if voltages on terminals 163 and 165 are like phased or in phase opposition then the currents in inductors 173, 175 will be different in phase by 90 degrees in a positive or in a negative sense.

For the case illustrated, since the transmitter source 41 is connected to the modulator 40 just prior to source 43, and since detectors 133 and 135 are responsive to currents of the frequencies of sources 41 and 43, it follows that the voltage on terminal 163 is leading that on terminal 165 by 90 degrees, thereby causing the currents in the inductors 173 and 175 to be like phased.

The inductors 173 and 175 are coupled to a pair of independently operating rectifiers 181, 182, by means of four secondary windings 177 to 180 inclusive. Preferably the inductors are equal, the couplings are equal and the mutual inductance between each secondary and its primary is the same as for any other secondary and its primary. One of the windings, such as 177 is reversely coupled, that is in an opposite sense to the others.

One end of coil 177 is connected to the anode of rectifier 181, the other end of 177 is connected through coil 178 to ground. The cathode of rectifier 181 is connected through resistor 183 to ground. The voltage impressed into this rectifier circuit is proportional to the vector sum of the currents in the coils 173 and 175. On the other hand, one end of coil 179 is connected to the anode of rectifier 182, the other end of coil 179 is connected through coil 180 and resistor 185 to the grounded cathode of rectifier 182. Here the couplings are such that rectifier 182 is driven in accordance with the vector difference of the currents in the coils 173 and 175. Condensers 184 and 186 are bridged across rectifier output resistors 183 and 185 for reduction of A. C. components in the output. For the case given, with voltage at the terminal 163 leading the voltage at terminal 165 by 90 electrical degrees, the rectified current through resistor 183

will be greatly in excess of the rectified current through resistor 185. On the other hand if the opposite phase relation held at the input terminals, the current through resistor 185 would greatly exceed that through resistor 183. If, however, the voltages at terminals 163 and 165 are like phased or oppositely phased, then the two currents in resistors 183 and 185 would be equal.

10. The cathode of tube 181 is connected through resistor 187, to the grid of a triode 190, for controlling a relay 92. The junction of coil 180 and resistor 185 likewise is connected through resistor 188 to the grid of triode 190. Resistors 183 and 185 are preferably equal, and resistors 187 and 188 are preferably equal but of much greater resistance than resistors 183 and 185. Condenser 189 may be connected from the grid of tube 190 to the ground line. The anode of tube 190 is connected through one winding 93 of relay 92 to the positive terminal of a battery 191, the negative terminal of which is grounded. The cathode of tube 190 is connected through resistor 195 to the positive terminal of battery 191, also through resistor 193 paralleled by condenser 194 to ground. Relay 92 is provided with an armature 90 having control over a lever which terminates in an insulating button 69 for jointly actuating two movable contact blades 97 and 98. Between these two contact blades is a stationary contact 96. The spring tensions of the contact blades are mutually opposed so as to normally hold the armature midway between the pole pieces of the relay coils 93 and 94. The armature position is, however, a function of the D. C. current in winding 93, this current being normally balanced by current through an opposing relay coil 94. A rheostat 95 is in circuit with coil 94 and by adjustment thereof the energization of coils 93 and 94 can be brought into mutual balance under the no-signal condition. The contact 96 is connected through a battery 199 to terminals of two D. C. motors 200 and 201, the other terminals of which are connected to the contacts 97 and 98.

The constants of the relay circuit are so chosen that when the grid of 190 is at ground potential, current flow through relay coil 93 will hold both contacts 97 and 98 open. This will occur when the outputs of the rectifiers 181, 182 are balanced so that the junction point of resistors 187 and 188 is at ground potential. When, however, the current through resistor 185 exceeds that through resistor 183 due to the voltage of terminal 163 leading the voltage of terminal 165, then the potential of the grid of tube 190 increases, and increased current in coil 93 causes contacts 96 and 98 to close, thus driving motor 200. This causes right operation of the rudder in accordance with operation of key 51 (Fig. 1) to right position R. If, however, the key 51 were at position L, then the voltage at terminal 163 would lag behind that at terminal 165, the current through resistor 185 would exceed that through resistor 183, and the grid of tube 190 would be negative with respect to ground. Under these circumstances, the current through relay coil 93 would be reduced, the armature 90 being then attracted predominantly by coil 94, thus producing a circuit closure through contact 97 which operates motor 201 for left rudder control.

Freedom from operation by unauthorized types of transmission will depend upon the lack of definite phase relationship at the input terminals.

163 and 165 of Fig. 3. Only when the signals are suitably phase-related will the rectified outputs of diodes 181 and 182 differ sufficiently to produce an effective change in the impedance of tube 190 and a resultant actuation of relay 92.

In Fig. 4 an alternative type of comparator is shown, with conditions corresponding to the voltage of terminal 164 lagging 90 electrical degrees with respect to that at terminal 166, as when this circuit is connected to corresponding numbered terminals of Fig. 3. This comparator does not require tuned circuits, and would be especially useful when the recurrent rate is quite low. In this figure both retarding and advancing circuits are employed between each input termination and the common ground. These circuits are cross-connected to two twin-triodes 210 and 211. One discharge path in each of these tubes is arranged to be actuated more strongly than the other.

The phase retarding and advancing circuits comprise elements 202 to 209 inclusive, all of which are of the same impedance at the operating frequency. Retarding circuit comprising resistor 202 in series with condenser 203 and advancing circuit comprising condenser 206 and resistor 207 are connected in parallel between terminals 164 and 168. Similarly retarding circuit comprising resistor 204 in series with condenser 205, and advancing circuit comprising condenser 208 in series with resistor 209 are connected in parallel between terminals 166 and 168. The junctions of elements 202 and 203, and of elements 204 and 205 are connected to the two control grids of twin-triode amplifier tube 210, and the junctions of elements 206 and 207, and of elements 208 and 209 are connected to the two control grids of twin-triode amplifier tube 211. The cathodes of these twin triodes are connected together and to the positive end of battery 212, the negative end of which is connected to grounded terminal 168. The negative end of battery 213 is connected to the cathodes, while the positive end of battery 213 is connected through resistor 214 to the two plates of tube 210 and through resistor 215 to the two plates of tube 211. These two twin-triodes 210 and 211 serve as mixing amplifiers, developing an output plate voltage in accordance with the vector sum of the voltage impressed upon the two grids.

For the arrangement given, with the voltage at terminal 166 advanced with respect to that at terminal 164, the two grids of 210 are energized out of phase, but the two grids of 211 are energized in phase. Therefore a large output voltage develops at the plates of 211, and little or no voltage at the plates of tube 210. If on the other hand, the voltage at terminal 164 should lead that at terminal 166 by 90 degrees, the tube 210 would develop large voltage and tube 211 a small voltage. For equal phased or reversed phased inputs, the tubes would produce equal outputs. Although desirable, it is not necessary that the input voltages be of the same magnitude.

The plates of tube 210 are connected through condenser 216 to the anode of rectifier 217, which in turn is connected through resistor 218 to ground. The cathode of rectifier 217 is connected through resistor 219 to ground, and this is shunted by condenser 220.

Similarly a rectifier output circuit is provided for plate output of tube 211 involving elements 221 to 225 inclusive. For the conditions shown, with the terminal 166 advanced in phase with respect to terminal 164, the rectified current

through resistor 224 will be much greater than that through resistor 219.

The cathode of rectifier 217 is connected to the grid of relay tube 226 and that of rectifier 222 is connected to the grid of relay tube 227. The cathodes of these tubes are connected together and through resistor 228 to ground, paralleled by condenser 229. The plate of triode 226 is connected through winding 230 and the plate of triode 227 through winding 231 of a balanced relay 232, to the positive end of battery 233, the negative end of which is connected to ground. Resistor 234 is connected between the positive end of battery 233 and the cathodes of tubes 226 and 227. The balanced relay 232 is provided with an armature 235 and with armature-controlled contacts 236 and 237. It responds to an unbalance of the currents through its two windings. Contact 236 is connected through motor 238 and contact 237 is connected through motor 239 to the negative end of battery 240, the positive end of which is connected to a stationary contact 241 which intervenes between the movable contacts 236 and 237.

In operation the circuits have been adjusted so that in the absence of signals, the tubes 226 and 227 pass little or no current. When in accordance with operation of key 52 of Fig. 1, the transmitter is modulated by source 44 (frequency f_4) and immediately thereafter by source 42 (frequency f_2) the receiver produces an A. C. voltage at terminal 166 which leads that at terminal 164 by 90 electrical degrees. This causes a large D. C. current to flow through resistor 224 and a very small D. C. current to flow through resistor 219, the latter current being zero when the magnitudes of the two A. C. voltages are equal. Tube 227 with its grid more positive than that of tube 226, causes the armature 235 of relay 232 to be drawn to the pole piece on which winding 231 is located, closing the contact 236 and rendering motor 238 operative to execute the control called for by key 52. If this key were in neutral, then the two currents would be equal and small, so that the armature 235 of relay 232 would be in neutral. For the key 52 on position U, the reverse phase relation would exist at the inputs of Fig. 4, and the motor 239 would be actuated. In the event of interference which actuates rectifiers 217 and 222 in an equal manner, there will be no output. By choosing the tubes 226 and 227 with square law characteristics, and providing a relay with little backlash, the operation of the system will be made independent of the amount of interference of random nature to a large degree.

It is evident that while the invention has been described on the basis of amplitude modulating a radio carrier, it can be practiced by other methods. For example, a radio carrier can be frequency modulated to produce a plurality of carrier frequency values in succession, and the currents necessary for operating the circuits of Fig. 2 may be produced by heterodyning the radiated frequency modulated signals. The frequencies of the series f_1, f_2, f_3, f_4 and f_5 herein referred to may, therefore, be considered variations of carrier frequency assignments, or as tone generator frequencies, according to the design of the apparatus.

In Fig. 5 the use of frequencies f_1, f_2, f_3, f_4 and f_5 is indicated, of which frequency f_3 may be considered serviceable only for camouflage purposes. A connection panel 501 comprises a plurality of jacks 502 each connected to one of the frequency sources or tone generators. Another series of

jacks 503 is suitably connected to contacts of two keys 504 and 505. Key 504 is illustratively shown as having the function of right and left steering. Key 505 has the function of up and down steering. For convenience the jacks of the 503 series are labeled *a*, *b*, *c*, *d* and *e*. By the use of jumper wires 506 the jacks 502 and 503 may be interconnected in any desired combination. The combinations may be changed from time to time according to a secret schedule. In this manner it will be difficult for an unauthorized recipient of the signals to analyze the system so as to determine what each signal means. Changes may be made from day to day or at predetermined times during the course of a run so that the difficulty of analysis would be greatly increased.

Key 504 has contacts *f* to *o* inclusive and key 505 has contacts *p* to *y* inclusive, arranged in alphabetical order. The interconnections between the key contacts and the jacks *a* to *e* inclusive are as follows:

Jack *a* is connected to movable contact *i*; jack *b* is connected to movable contact *k*; jack *c* has branched connections to contacts *f*, *n* and *y*; jack *d* is connected to movable contact *t*, and jack *e* is connected to movable contact *v*. Contacts *g*, *o* and *q* are interconnected; contacts *h* and *l* are interconnected and are also connected to segment 1 on a rotary distributor switch 47' similar to distributor 47 in Fig. 1. Contact *j* is connected to segment 2 on distributor 47'; contacts *m* and *p* are interconnected; contacts *r* and *x* are interconnected; contacts *s* and *w* are interconnected and are also connected to segment 3 on distributor 47'; contact *u* is connected to segment 4 on distributor 47'.

With the key contact connections arranged as shown it is possible to transmit signals for left or right rudder control and for up or down elevator control and these signals may be transmitted singly or together. Whenever they are transmitted singly the camouflage frequency *f*₃ is transmitted on one segment of the unused half of the distributor 47'. The following table shows the correlation between key contact closures, and the connections from the jacks *a*, *b*, *c*, *d*, *e* to the commutator segments 1, 2, 3 and 4:

Operation	Closure of contact pairs		Jack Connections to Segments			
	Key 504	Key 505	1	2	3	4
Right only...	<i>fg, hi, jk, mn</i>	<i>gr, ij, kl, no</i>	<i>a</i>	<i>b</i>	<i>c</i>	--
Left only...	<i>gh, ij, kl, no</i>	<i>gr, ij, kl, no</i>	<i>b</i>	<i>a</i>	<i>c</i>	--
Up only...	<i>gh, mn</i>	<i>gr, st, uv, wx</i>	<i>c</i>	<i>---</i>	<i>d</i>	<i>e</i>
Down only...	<i>gh, mn</i>	<i>gr, tu, vw, xy</i>	<i>c</i>	<i>---</i>	<i>e</i>	<i>d</i>
Right-up...	<i>fg, hi, jk, mn</i>	<i>gr, st, uv, wx</i>	<i>a</i>	<i>b</i>	<i>d</i>	<i>e</i>
Left-up...	<i>gh, ij, kl, no</i>	<i>gr, st, uv, wx</i>	<i>b</i>	<i>a</i>	<i>d</i>	<i>e</i>
Right-down...	<i>fg, hi, jk, mn</i>	<i>gr, tu, vw, xy</i>	<i>a</i>	<i>b</i>	<i>e</i>	<i>d</i>
Left-down...	<i>gh, ij, kl, no</i>	<i>gr, tu, vw, xy</i>	<i>b</i>	<i>a</i>	<i>e</i>	<i>d</i>

In connection with the above table, it should be pointed out at this juncture that the keys 504 and 505 are of the type known and used extensively in telephone practice as "anti-capacity switches," being of the four-pole double-throw type. Such switches are actuated by a cam roller, and standard keys or switches of this type have the springs carrying contacts *i* and *k*, and *t* and *v*, under tension such as to hold the corresponding key in a central position. Under these conditions, whenever key 504 is moved to execute "Right" operation (handle of key 504 moved to the right) contact *i* is moved to the left by the

cam roller to establish contact with *h*, and at the same time, because of its tension, the spring carrying contact *k* moves to the left to establish contact with *j*. Similarly, for "Left" operation (handle of key 504 moved to the left) contact *k* is moved to the right by the cam roller to establish contact with *l*, and at the same time, because of its tension, the spring carrying contact *i* moves to the right to establish contact with *j*. The center contact *j* of course need not move much from the position shown in Fig. 5. A similar explanation is applicable to key 505, so that the accuracy of the preceding table should now be apparent.

Fig. 5 also shows modifications of receiving arrangements where the comparators 31 and 32 are fed with filtered output components from the units 133, 135, 134 and 136 with intervening jack panel and jumper wire connections for adapting 10 the signal responses to the permutational arrangement of frequencies which at any time may be set up on the jack panel at the transmitter for assignment to the contacts of keys 504 and 505.

The receiver circuit components between the 25 antenna 100 and the terminals 163, 165, 164 and 166 may be the same as shown in Fig. 2, and for this reason such circuit components are not repeatedly shown in Fig. 5. They are indicated in their entirety by the rectangle labeled "Circuit arrangement of Fig. 2." The comparators 31 and 32 correspond respectively with either of the circuit arrangements shown in Figs. 3 and 4. The output circuits for these comparators supply suitable currents for driving the rudder motors 200, 201, 238 and 239, the same as is shown in either of the modifications of Fig. 3 and Fig. 4.

So far as the modification of the receiving equipment is concerned the only change indicated in Fig. 5 is that of introducing alternative connections between the filter circuits 133, 135, 134 and 136 and the input circuits 33, 35, 34 and 36 of the two comparators 31 and 32. Jumper wires 37 may, therefore, be used for interconnecting the jacks in suitable combinations, thus facilitating the changing of the permutations for the different controls in accordance with a prearranged schedule. The right, left, up and down steering controls may, therefore, be made to conform to the intended remote control significance of the signals as transmitted, changes being made from time to time in the permutational arrangement of the tone generator frequencies in order 50 to confuse an unauthorized recipient of the signals.

The frequency allotments to the transmitting distributor segments are subject to a certain number of permutational variations. Thus, for example, assuming that only four frequency selective filters are to be provided at the receiving station, and that the camouflage frequency *f*₃ will not be interchanged with any other frequency, then in place of the connection of source *f*₁ to jack *a*, either of the sources *f*₂, *f*₄ or *f*₅ may be connected. With each of these substitutions the remaining frequency sources may be allotted to the other jacks in different sequences, making 60 24 possible permutations. Since a receiving commutator has been found unnecessary, however, the starting point for any sequence of signal elements is not distinguishable. Therefore, only six of the 24 possible permutations are really useful 70 as follows:

Permutation	Source			
	f_1	f_2	f_3	f_4
#1	a	b	d	e
#2	a	b	e	d
#3	b	e	a	d
#4	b	a	d	e
#5	d	a	e	b
#6	e	d	b	a

If desired, an additional frequency-selective filter may be provided at the receiver for acceptance of frequency f_3 . Then this frequency can be used as a substitute for any of the other frequencies for control purposes and the displaced frequency can be used temporarily as a camouflage frequency. In this case the output from the additional f_3 filter may be fed through an additional jack to a predetermined one of the comparator input terminals of the series 33-36.

When provision is made for interchanging five or more frequencies certain of the possible combinations will not exercise control and can be used from time to time for camouflage purposes. In this manner the difficulty of decoding the signals by an unauthorized recipient will be still further increased.

Other modifications of my invention may readily be made by those skilled in the art, in view of the foregoing description. Such modifications will be understood to be comprehended within the scope of my invention.

I claim:

1. A remote control system comprising a plurality of alternating current regenerators, each productive of a different frequency, a radiant energy transmitter including means for modulating a carrier wave, means including a driven multiplex distributor and a keying device for automatically connecting selected ones of said generators in repeated sequences to said modulating means, said keying device including means to vary the sequence of the generator connections, a receiver comprising selective means for discriminating between the respective frequencies of the signals originated at said transmitter and detecting means for each of said different frequencies coupled to said discriminating means for producing voltages corresponding in time sequence to the sequence of modulation of said carrier wave by the alternating currents, and phase displacing means in combination with detecting means for combining said voltages to produce a chosen remote control effect.

2. In a remote control system transmitting apparatus comprising means for keying and modulating a carrier wave with a train of recurrent signal elements each element of which is characterized as a predetermined control frequency, a driven multiplex distributor for transmitting said signal elements in repeated sequences in pairs, receiving apparatus including amplifier, discriminator and detector stages and circuits for shifting the phase of certain low frequency components which are products of detection, and phase-comparator circuits for producing a control voltage the relative positive polarity of which depends upon whether the detection products of two paired signal elements are combined in phase agreement or contraphasally.

3. The combination according to claim 2 and including means for interjecting into said train of signal elements other signal elements rectification of which is to confuse an unauthorized recipient of the signals.

4. The combination according to claim 2 and including means associated with the transmitting apparatus and with the receiving apparatus for transposing the positions of the signal elements of each pair in the sequence of transmission.

5. In a radio controlled system for steering a dirigible body, the combination with motor means for setting the rudder to either side of a neutral position, of a three-position relay having two energizing coils and contacts for reversibly actuating said motor means, electron tube circuit means for selecting and detecting signal pulses of different frequency characteristics recurring at a fixed rate and a known sequence which may be changeable to derive characteristic potentials, and means controlled by said potentials for differentially actuating the coils of said relay in accordance with the particular sequence of reception of said pulses.

20 6. In a signaling system, means for generating and radiating carrier frequency energy, a modulator circuit to which said means is coupled, means for generating modulation frequency energies of different frequencies, keying means and 25 commutating means coupling said last-named generating means to said modulator circuit for applying pulses of energy of different frequencies from said modulation frequency generating means to said modulator circuit in sequence at 30 a substantially fixed pulse rate, said pulses being characterized by different frequencies which appear in a predetermined but changeable sequence, remotely situated receiving and demodulating means, means for discriminating between different demodulation products of the received signal pulses which possess said different frequency characteristics, phase-shifting devices operable at a frequency equal to the said pulse rate and effective to combine said demodulation products, and reversibly operable relay means suitably coupled to said phase-shifting devices whereby the sense of the relay operation is made dependent upon the sequence of the modulation frequency pulses.

45 7. The combination according to claim 6 and including mutually opposed motor means for steering a dirigible body, and circuits controlled by said relay means for selectively actuating said motor means thereby to steer said body in a direction which is determined by the joint control significance of said pulses.

8. The combination according to claim 6 and including a four-channel distributor in said commutating means and at least two pairs of contacts in said keying means coupling said second generating means to said modulator to provide for the transmission of modulation pulses in pairs, separate controls for said keying means to separately or combinedly transmit one pulse pair for right-left steering control upon a dirigible body and one pulse pair for up-down elevator control upon said body.

9. The combination according to claim 6 and including a multi-channel distributor in said commutating means and contacts in said keying means for feeding modulation frequency energies selectively to different channel components of said commutating means, certain of said channel components then functioning to transmit signals as desired for remote control purposes and at least one of said channel components of said commutating means being selectable to transmit a signal pulse for camouflage purposes.

10. In a remote control system for a steering device responsive to carrier currents modulated

in repeated sequence at a constant predetermined rate by at least two currents of different frequencies wherein the time sequence of the modulating currents is altered for control purposes, a frequency discriminator and detector system excited by said modulated carrier currents for deriving pulses of A.-C. the pulse frequency of which corresponds to said constant rate and the relative times of occurrence of which change when said sequence is altered, and control apparatus responsive to said pulses of A.-C. for controlling said steering device.

ELLISON S. PURINGTON.
